UNITED STATES PATENT OFFICE.

ELIE RICHARD, OF QUEBEC, QUEBEC, CANADA.

LEATHER-PRESS.

1,375,469.

Specification of Letters Patent. Patented Apr. 19, 1921.

Application filed October 23, 1919. Serial No. 332,721.

To all whom it may concern:

Be it known that I, ELIE RICHARD, a subject of the King of England, residing at Quebec, in the Province of Quebec, Dominion of Canada, have invented certain new and useful Improvements in Leather-Presses, of which the following is a specification.

The present invention relates to improvements in leather presses, and its main object is to provide a device of this character whereby the coarse leather is pressed and polished in one operation, thus saving time and labor and reducing the cost of manufacture.

Another object is to provide a machine simple and particularly cheap of construction.

The invention will be better understood with the aid of the accompanying drawings in which:

Figure 1 is a side elevation of the machine.

Fig. 2 is a front elevation.

Fig. 3 is a vertical section of the machine on line A—A of Fig. 2.

Fig. 4 is a vertical section of the machine on line B—B of Fig. 1.

Like numerals of reference indicate corresponding parts in each figure.

In the drawings, 1 is a base having an upwardly projecting over-hanging head 2, and 3 is a horizontal channel provided at one end thereof with an enlarged portion 4. Communicating with said enlarged portion 35 4 is a hole 5 which also communicates with a vertical hole 6.

7 is a shaft suitably journaled in the said horizontal channel 3, which shaft projects through the channel to the rear of the base 1.

40 The forward end of said shaft is provided with an eccentric 8 which turns in suitable bearings in the enlarged portion 4 of the channel. A gear 9 is rigidly mounted on the rear end of the said shaft, and a block 10 is adapted to saddle the eccentric 8 and move in the hole 5.

In the hole 6 is movably mounted the cylinder 11, said cylinder being adapted to sit or rest on the block 10. The cylinder 11 is provided with an inlet port 12 to permit the entrance of the compressed oil, air, or water into the bottom of said cylinder which will actuate the plunger 13, on which is provided the table or jaw 14.

55 The over-hanging head 2 is provided with a pivotally mounted table or jaw 15 which

is hollow and provided with zig-zag channels 16 in which steam circulates, entering through the opening 17. The object is to heat this jaw in order that it will heat-up the leather and give to the same a polished surface. The jaw 15 is automatically swung on its pivot as indicated in Fig. 1 by a centrally fulcrumed lever 18 which is pivotally connected at one end to said jaw 15 by the link 19; and 20 is a downwardly projecting and pivoted rod provided at the other end of said lever 18 and having at its lower end a roller 21 which engages the eccentric channel 22 which is provided at one side of the gear 9. Thus when the gear 9 revolves the eccentric channel will actuate the lever 18 and tilt the jaw 15.

In the rear of the base or frame 1 is provided an upwardly projecting bracket 23 in which is suitably journaled the shaft 24 on which shaft is loosely mounted the pulley 25. A clutch 26 is slidably mounted on said shaft, and a gear 27 is also mounted thereon, and adapted to co-act with the gear 9 mounted on the shaft 7.

The clutch 26 is operated by the lever 28 which, in turn, is operated by a lever 29 pivotally connected at 30 in the bracket 23. Lever 29 is provided at one end with a weight 31, and has connected to it a cord 32 which passes over the pulley 33 and which terminates in an operating part 34. The lever 28 is pivotally connected intermediate thereof to said lever 29 by the short link 35, 90 and 36 is a pin pivotally connected to the lower end of said lever 28 and slidably mounted in the guide 37. Said pin 36 is adapted to engage one of the holes 38 which are provided in the circumference of the gear 9, thus locking said gear at predetermined points.

In the operation of the invention the lever 29 is raised in the dotted line position illustrated in Fig. 1 of the drawings which pulls the pin 36 out of the hole 38 in the gear 9 and thereby unlocks the gear, the operation of lever 29 simultaneously sliding the clutch 26 into engagement with the pulley 25, to impart motion to the shaft 24 and the gear 27. The gear 27 will revolve the gear 9 and eccentric 8, thus lifting the block 10 which carries the movable cylinder 11, plunger 13 and jaw 14. Simultaneously the eccentric channel 22 on the gear 9 will move lever 18 110 into the horizontal position indicated in dotted lines in Fig. 1 of the drawings. There-

fore the mechanical action is to raise the jaw 14 so that it will contact with the jaw 15 when the pressure oil, air or water is forced through the port 12 in the cylinder 11 which 5 raises the plunger 13 and compresses the jaw 14 against the jaw 15. The leather which is disposed between the jaws is thus pressed and given a polished surface by the heated jaw 15.

10 To remove the pressed leather from between the jaws, the operation is reversed, which lowers the jaw 14 and the cylinder 11 into their primitive position and tilts the jaw 15 in order to provide a wider space to 15 easily remove or insert the leather.

I claim as my invention:—

1. In a press, the combination of a base provided with a pair of superposed openings; a cylinder movable vertically in the 20 upper opening; mechanism located in the lower opening for positively operating on the cylinder to bodily raise and lower it; a piston in said cylinder; means for effecting vertical movement of the piston independently of and relatively to the cylinder; a jaw secured to the piston to move therewith; and a jaw coöperative with the first jaw.

2. In a press, the combination of a base provided with a pair of superposed openings; a cylinder movable vertically in the upper opening; a saddle block and an eccentric for raising and lowering the same located in the lower opening for bodily raising and lowering the cylinder; a jaw mounted 35 to move with said cylinder; and a jaw coöperative with the first jaw.

3. In a press, the combination of a base provided with a pair of superposed openings; a cylinder movable vertically in the 40 upper opening; a saddle block and an eccentric for raising and lowering the same located in the lower opening for bodily raising and lowering the cylinder; a piston in said cylinder; means for effecting vertical movement of the piston independently of and relatively to the cylinder; a jaw secured to the piston to move therewith; and a jaw coöperative with the first jaw.

4. In a press, the combination of a base; 50 a vertically-movable jaw mounted thereon; operating mechanism therefor; a tiltable jaw coöperative with the first jaw; and connections between said operating mechanism and the second jaw for automatically tilting the latter into active position simultaneously with the upward movement of the first jaw.

5. In a press, the combination of a base, a vertically-movable jaw mounted thereon; operating mechanism therefor; a tiltable 60 jaw coöperative with the first jaw, and connections between said operating mechanism and the second jaw for automatically tilting the latter into active position when the former starts to operate.

65 6. In a press, the combination of a base;

a vertically-movable jaw mounted thereon; operating mechanism therefor including a rotatable main element; a tiltable jaw coöperative with the first jaw; and a common means for driving said rotatable element and tilting the second jaw into active position.

7. In a press, the combination of a vertically-movable jaw; a tiltable jaw coöperative therewith; a device for raising and lowering the first jaw; a lever connected to tilt 75 the second jaw into active position; and a common operating element for said device and said lever.

8. In a press, the combination of a vertically-movable jaw; a tiltable jaw coöperative therewith; a device for raising and lowering the first jaw; a rotatable driving element for said device; a lever connected to tilt the second jaw into active position; and connections between said driving element 85 and said lever for operating the latter during the rotation of the former.

9. In a press, the combination of a vertically-movable jaw; a shaft; an eccentric on said shaft for raising and lowering said jaw; a rotatable driving element on said shaft; a tiltable jaw coöperative with the first jaw; and a device for tilting the second jaw into active position connected to be automatically operated by said driving element. 90

10. In a press, the combination of a bodily movable jaw; a jaw coöperative therewith; a rotatable operating device for the first jaw; a rotatable driving element on said device; a main drive shaft; a clutch thereon; driving connections between the main shaft and said driving element; means for locking said driving element against rotation; and means for simultaneously unlocking said driving element and closing 105 said clutch.

11. In a press, the combination of relatively stationary and movable jaws; operating mechanism for the movable jaw; a main shaft connected to drive said mechanism and provided with a clutch; means for locking said mechanism again operation; and means for simultaneously releasing said locking means and closing said clutch. 110

12. In a press, the combination of relatively stationary and movable jaws; operating mechanism for the movable jaw including a rotatable element; a main shaft connected to drive said element; a clutch on said main shaft; a member movable into engagement with said element to lock the same against rotation; and a common means for withdrawing said member and closing said clutch. 120

13. In a press, the combination of relatively stationary and movable jaws; operating mechanism for the movable jaw including a rotatable element; a main shaft connected to drive said element; a clutch on said main shaft; a member movable into en- 125

130

gagement with said element to lock the same against rotation; and means for simultaneously disengaging said member and closing said clutch.

5 14. In a press, the combination of relatively stationary and movable jaws; operating mechanism for the movable jaw including a rotatable element; a main shaft connected to drive said element; a clutch on

10 said main shaft; a member movable into engagement with said element to lock the same against rotation; a lever connected at one end to the clutch and at the other end to the locking member to simultaneously 15 control the activity of both said clutch and said locking member; and operating means for said lever.

15. In a press, the combination of a bodily movable jaw; a tiltable jaw coöperative 20 therewith; operating mechanism for the first jaw including a rotatable driving element; a lever for tilting the second jaw into active position; operating connections for said lever engaged with one side of said driving 25 element; a main drive shaft connected to rotate said driving element and provided with a clutch; a locking member engageable with the other side of said driving element; and means for simultaneously disengaging 30 said member and closing said clutch.

16. In a press, the combination of a bodily movable jaw; a tiltable jaw coöperative therewith; operating mechanism for the first 35 jaw including a rotatable driving element; a lever for tilting the second jaw into active

position; operating connections for said lever engaged with one side of said driving element; a main drive shaft connected to rotate said driving element and provided with a clutch; a locking member engageable with the other side of said driving element; and means for disengaging said member and closing said clutch. 40

17. In a press, the combination of relatively stationary and movable jaws; an eccentric 45 for operating the movable jaw; a shaft whereon said eccentric is mounted; a gear on said shaft; driving means for said gear including a clutch to control its rotation; a locking member engageable with 50 said gear; and means for disengaging said locking member and closing said clutch.

18. In a press, the combination of a base provided with an opening; a cylinder loosely mounted therein; a device mounted 55 in said base beneath said opening for operating positively on said cylinder to bodily raise and lower it; a piston mounted in said cylinder and provided with a jaw; means for supplying motive fluid to said 60 cylinder to raise the piston relatively to the cylinder; and a jaw coöperative with the first jaw.

Signed at Quebec, Province of Quebec, Canada, this 18th day of July, 1919.
